UNITED STATES PATENT OFFICE.

GEORGE W. BOTHWELL, OF ONTARIO, CALIFORNIA.

HEATER.

REISSUED

1,116,789.

Specification of Letters Patent.

Patented Nov. 10, 1914.

Application filed April 24, 1913. Serial No. 763,438.

To all whom it may concern:

Be it known that I, GEORGE W. BOTHWELL, a citizen of the United States, residing at Ontario, in the county of San Bernardino 5 and State of California, have invented a new and useful Heater, of which the following is a specification.

This invention is particularly intended for use as an orchard heater, although it is applicable for other purposes. The heater is of the type wherein the oil or liquid fuel is vaporized in a generator before it is burned, and the main object of the invention is to provide for preventing backflow of vapor 15 to the supply tank or reservoir without the use of a check valve, and with minimum head or pressure on the supply of oil.

Another object of the invention is to prevent production of undue pressure in the 20 generator.

The accompanying drawings illustrate embodiments of the invention, and referring thereto:

Figure 1 is a vertical section of the heater, 25 its supply reservoir being shown partly in elevation. Fig. 2 is a horizontal section on line x^2-x^2 , in Fig. 1. Fig. 3 is a sectional view showing the burner outlet. Fig. 4 is a vertical section of a modified form of the 30 heater. Fig. 5 is a plan view of the generator and burner tube of the form shown in Fig. 4. Fig. 6 is a section on line x^6-x^6 , in Fig. 4.

Referring to Figs. 1 and 2, the heater 35 shown therein comprises a casing or pot 1, having a cover 2, provided with a stack 3, said casing being provided at one side with an air inlet opening 4, through which extends the oil or fuel supply pipe 5. A portion 40 of pipe 5 within the casing 1 is formed as a generator or retort said pipe being bent around, for example, in approximately circular shape, and terminating in a vapor outlet 7, formed in a cap 8 at the end of the pipe. Said generator portion of the pipe 45 may be bent up, as at 9, to prevent oil from running out of the generator when cold.

Oil supply pipe 5 is connected to a pipe

10, communicating with a suitable source of oil supply, for example a tank or reservoir 50 11, which may, as shown, be provided with an outlet chamber communicating with the interior of the reservoir by means of an opening 13, and having a vent 14, whereby oil is only allowed to flow into said outlet 55 chamber in sufficient amount to keep the oil level therein at a definite level. Any other suitable means for supplying oil may be used. I prefer to provide a manually operated valve 15, in the oil pipe 10.

Pipe 10 is provided with a downwardly extending or U-shaped bend 16, forming a trap, and a vent pipe 17 leads upwardly from the end of this bend nearer the generator, and is preferably open at the top.

The operation is as follows: Valve 15 being opened, oil flows from tank 11 to the pipes 10 and 5, and fire being started in the casing 1, by burning light oil or rubbish therein, the generator is heated sufficiently 70 to cause vaporization of the oil in the generator, and the vapor, issuing from the outlet 7, burns in a flame which passes around within the casing and in contact with the generator, so as to maintain the heat of the 75 generator, the products of combustion eventually passing up through the stack. The production of the vapor in the generator develops considerable back pressure, tending to force oil and vapor back into the 80 reservoir 11. This tendency is resisted by the down bend 16 in the pipe, and the vapor passing back in pipe 5 escapes upwardly in the vent pipe 17, being mostly condensed in this pipe 17 and flowing back into pipe 5. 85 By reason of the described operation of the trap and vent in the oil supply pipe, I am enabled to use an oil supply having very little pressure, and am enabled to use a horizontally extending generator having little 90 if any rise for retaining the oil.

The heater casing may be of any suitable form, for example, and L-shaped tubular structure of stove pipe, as shown at 24 in Figs. 4 and 6, the generator being in that 95 case an elongated coil 25, having an outlet

26. This figure also shows a modification of the trap which is here shown as a circular or helical bend 27 in the oil pipe 28.

What I claim is:

5 A heater comprising a generator having a burner outlet, a supply pipe for liquid fuel, connected to said generator, and provided with a downwardly extending U-shaped bend, acting as a trap for vapor passing from the generator, and a vent pipe lead-

ing from said pipe between the trap and the generator.

In testimony whereof, I have hereunto set my hand at Los Angeles, California, this 17th day of April, 1913.

GEORGE W. BOTHWELL.

In presence of—

ARTHUR P. KNIGHT,
F. ALICE CRANDALL.
